[57] **CLAIM**

The ornamental design for an electrical outlet cover plate and closure therefor, substantially as shown and described.

DESCRIPTION

FIG. 1 is a top perspective view of an electrical outlet cover plate and closure therefor showing my new design in the closed position;

FIG. 2 is a perspective view in the opened position;

FIG. 3 is a bottom perspective view in the closed position;

FIG. 4 is a bottom perspective view in the opened position;

FIG. 5 is a rear edge elevational view thereof;

FIG. 6 is a top plan view thereof;

FIG. 7 is a side elevational view taken from the front of FIG. 1.
